FRANK J. KOCH, OF NEWARK, NEW JERSEY

SEWAGE EJECTOR

Application filed February 26, 1930. Serial No. 431,582.

The present invention relates to a novel apparatus for disposing of sewage and more particularly to means for pneumatically ejecting sewage from a container and forcing it into a discharge pipe.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a diagrammatic view showing a simple embodiment of the present invention;

Fig. 2 is a detail elevation, partly in section, of a contact device employed in connection with the present invention, and forming a part thereof;

Fig. 3 is a diagrammatic view showing a modified form of the invention;

Fig. 4 is a diagrammatic view showing a further modification of the invention; and

Figs. 5 and 6 are diagrammatic views showing a modification of the invention in which the mechanism is adapted for automatic operation.

The present invention has for its object the provision of an apparatus for pneumatically ejecting sewage from a container into which it has been fed, and provides means for readily handling large quantities of sewage in an efficient and sanitary manner. According to certain features of the invention, there are provided means for completely au-

tomatically controlling the operation of the mechanism thereby avoiding the necessity of continuous attention to the mechanism on the part of the operator.

Other features of the invention will be initially pointed out in connection with the following detailed descriptions of the present preferred embodiment of the invention, and it will be understood that the foregoing general description and the following detailed description are both exemplary and explanatory, but not restrictive of the invention.

Figure 1 of the drawings shows a relatively simple embodiment of the present invention wherein there is provided a container 10 adapted to receive the sewage after it has been screened, and this container preferably comprises a generally frusto-conical tank having a reduced cylindrical upper portion 11 with a flared mouth 12 and provided with a gate 13 pivoted at one side of the mouth and adapted to be swung upwardly to seal the opening at the top of the container. For operating the gate 13 there is provided a lever 14, attached to the gate and pivotally connected with the piston 15 of the pneumatic cylinder 16 for the gate, so that the gate 13 is closed and opened as air is admitted to or released from the cylinder 16. At the bottom of the container is a sliding gate 17 adapted to open the passage from the container to the discharge pipe 18, and this gate is actuated by means of lever 19 pivoted on the side of the container and connected with the pneumatic actuating piston 20.

For indicating to the operator the level of the sewage in the container and enabling the operator to determine when the gate 13 should be closed for the discharge of the sewage from the container, there is provided a contact device in circuit with signalling means, the contact device being closed when the sewage reaches a predetermined level 90

in the container. As embodied, the signal means preferably comprise a visual and an audible signal, such as a lamp 21 and an electric bell 22, which are energized by current supplied from a source of power 23, the supply of current to the bell and lamp being controlled by relay 24, the movable contact 25 of which is moved to circuit closing position by closing of the circuit through contact device.

10 As embodied, the contact device (Fig. 2) preferably comprises a metallic conducting member 26 pivotally supported by a rod 27 projecting into the container 10 and conducting member 26 hangs downwardly with the casing, and it and rod 27 are insulated from the casing by means of insulation 28. Insulation 28 is preferably surrounded by a pipe 29 which can be threadedly secured within an aperture in the upper portion 11 of the container. The connections for said contact device are made as follows:—One side of the line is attached to the rod 27 by means of nut 30 while the other side is grounded or otherwise connected with the metallic container, and the circuit is closed by contact of the liquid sewage with the lower depending end of conducting member 26, so that the current passes from the container 10 to the conducting member 26 through the liquid sewage.

15 It is generally desirable to employ two containers, discharging into a single discharge pipe, so that one of the containers may be filled while the other is being discharged. As shown in Figure 3 of the drawings there are provided two containers 10, substantially similar to that already described, and having their discharge outlets 18 connected to a single discharge pipe 32.

20 Each container is provided with a discharge gate 17 and a pneumatic cylinder 34 for opening and closing the gate and is also provided with a gate 35 for the upper opening of the container, together with pneumatic cylinders 16 for opening and closing these gates.

25 As embodied, the cylinders and gates 34, 17 and 16, 35 are adapted to be simultaneously and oppositely operated, and each cylinder 34 and 35 is connected with an air pipe at each of its ends. For actuating these gates, there is preferably provided a source of compressed air 37, and to allow the pistons to be reversely moved, there is provided a relief pipe 38 through which the air is released from the cylinders. As embodied, the flow of air to and from each cylinder is preferably controlled by a single four way valve 39 through which compressed air may be supplied to the cylinders to open discharge gate 17 and close gate 35, after which the pressure within the container may be increased forcing the sewage out of the container and into the discharge pipe 32, as shown in Figure 3. On turning valve 39, 90°, after the

sewage is completely discharged, gate 35 returns to its position to close the discharge opening of the container while the air from the cylinders 16 and 34 is released through pipe 40, the gates being opened by its own weight as the pressure is reduced. The apparatus is then ready to be again filled with sewage.

30 According to a modified embodiment of the invention, as illustrated in Figure 4 of the present drawings, means are provided for electrically controlling the operation of the sewage ejecting mechanism, and for preventing the discharge from one of the containers until another has completed the discharging operation, thereby preventing the sewage from being blown from one of the containers into the other. Also, means are preferably provided for indicating to the operator the upper and lower levels of the sewage in the container thereby enabling the operator to supply compressed air to the container exactly in accordance with the needs of the apparatus.

35 As embodied, the container 10 is substantially identical with the containers described in connection with the previously described modifications of the invention, and need not be described in detail. The container is provided with a contact device 50, similar to the one already described for indicating the upper level of the sewage in the container 10, and this contact device is in circuit with signalling means, such as bell 51 and lamp 52, to inform the operator when the container 100 has been filled and warn him to stop the flow of sewage to the container. Another contact device 53 is provided for automatically interrupting the flow of compressed air to the interior of the container when the sewage in the container has been forced out of the container below a predetermined lower level.

40 For controlling the supply of compressed air to the container, there is preferably provided an electromagnetically controlled three-way valve 54 in the air line 55, the electromagnet 56 of the valve being energized by closing the electric circuit from the source of power G to the valve by means of manually-operated switch 57 through relay 58. For preventing opening of the valve when the sewage is at too low a level in the container 10, the circuit for the electromagnetic valve 54, preferably includes the contact device 53 for the lower level of sewage in series with the electromagnet 56 so that relay 58 can be closed to energize the magnet only when sewage is closing the circuit between the sides of the container 10 and the contact member 53.

45 Means are also provided for preventing the discharge of sewage from one of the containers while another is being discharged, and for this purpose, the circuit for the electromagnetic valve of each container includes

a relay in series with the valve operating electromagnet of the other containers, and connected therewith, the relay being adapted to open a switch in series with the electromagnet for the container while it is being operated. As embodied, relay 59 has its electromagnet in series with the electromagnetically controlled valves 54 shown in Figure 4, and opens switch 62 which is in series with the electromagnet 56 of the valves 54 for the other containers and connected therewith by conductors 61 and a similar switch across the conductors 60, is also provided for controlling the valve 54 of the container shown in Figure 4.

For releasing the air from the container after the level of the sewage has been lowered in the container 10, there is provided an exhaust pipe 64, which is automatically connected with the air line 55 leading to the container, by closure of the electromagnetically controlled valve 54.

In order to provide for continued operation of the sewage disposal apparatus, in case of a failure of power to operate the electromagnetically controlled valves, means are also preferably provided for manually controlling the supply of air to the container, and as embodied, there is provided a three-way valve 65 controlling the supply of air from the compressor, and the release of the air from the container 10 through relief pipe 66 when the upper gate is to be opened. A valve 67 is also provided to prevent the escape of air through the relief pipe 64, and another valve 68 to prevent air being passed through valve 54, and a by-pass 69 is provided around these valves 67 and 68, the by-pass in turn being controlled by a valve 70, so that it can be rendered normally inoperative during the electrical operation of the apparatus.

In the modified embodiment of the invention shown in Figs. 5 and 6, there is provided a container 10, of generally conical shape, provided with a restricted top through which the sewage may be fed into the container as it is delivered to the container by the discharge of the screening mechanism. The top of the container is provided with means for forming a substantially air tight seal, preferably comprising a gate 35 pivotally mounted in the restricted opening at the top of the container, the closing of the gate being controlled by a suitable electromagnetically operated air valve controlling the air supplied to the gate operating cylinder.

Means are provided for controlling the discharge of the sewage contained in the container, and as embodied, there is provided an electro-pneumatically operated valve at the lower end of the container, controlling the passage of the sewage from the container into the discharge pipe. As embodied, there is provided a cylinder and piston connected

with the discharge valve, and an electro-magnetically operated valve controlling the admission of the compressed air to each side of the piston, thereby to close or to open the discharge valve.

Means are provided for ejecting the sewage in the container after the inlet gate at the top of the container has been closed, and the discharge valve at the bottom of the container has been opened, and as embodied there is provided an electro-magnetically operated valve controlling the admission of air to the upper portion of the sewage container, so that as the valve is opened, the air pressure above the sewage is increased to blow the sewage out of the container, through the discharge valve and into the discharge pipe with which the container is connected.

Means are also provided for automatically controlling the operation of the several parts above described, and, as embodied, there is provided a rod 53 with which the contents of the container are adapted to contact to close an electric circuit when the container has been filled with sewage to a predetermined level. Preferably the rod is formed of electrically conducting material and is insulated from and supported by the top of the container, from which it extends downwardly into the container. The container is formed of electrically conducting material and when filled with sewage the electric circuit between the rod and the container is completed by the liquid sewage, which has sufficient electric conductivity to effect the desired closing of the circuit.

As embodied, there are provided means for automatically setting the various parts of the mechanism into operation as soon as the container has been filled with sewage to the predetermined level, which will now be described.

An instrument panel 99 is provided for each of the sewage ejectors to be operated and these panels are supplied with electric energy from a generator 100 through mains 101, 102 and 103, connected with an electric motor 105 mounted on the instrument panel for rotating the cam shaft 106. A three-pole manually actuated switch 107 is provided in circuit with the motor and this, together with the electrically actuated switch 108, controls the rotation of the motor 105. The cam shaft 106 is provided with suitable cams for controlling the opening and closing of the switches 111, 112, 113, 114, 115, 116, 117, 118, 119, 120, 121, 122, 123, 124 and 125, these switches in turn controlling the several branch circuits which will be later described.

As sewage is run into the container 10, the motor 105 remains stationary until the sewage contacts with the lower end of rod 53, closing the circuit between the metallic walls of the container and the rod 53, thereby estab-

lishing an electric circuit which may be traced as follows:—

From main 102 through an electro-magnetically operated tumbler switch 126 to rod 53, container 10, and back to cam operated switch 122 and through this switch to main 101. The current flowing in this circuit energizes the magnet of switch 126 throwing the switch arms to their alternate position and breaking the previously established circuit and establishing a circuit from main 102 to switch 123, at the same time closing the circuit from main 101 through the normally open contact 130 of switch 126 to cam operated switch 111, from thence through cam operated switches 114, 115, 117 and 119, energizing the solenoid 131 of electrically actuated switch 108, thereby closing the motor circuit and starting the motor 105. As cam motor 105 rotates switch 111 is closed energizing the magnet of relay 139, and also closing cam operated switch 112 and opening cam operated switch 113. On further rotation of the motor 105 air valve 132 is opened admitting air to the cylinder 16 for closing the gate 35 at the top of the container, at the same time opening cam operated switch 114, breaking the holding circuit, energizing solenoid 131, and automatically opening switch 108.

The motor 105 now remains at rest until the gate 35 has been raised to its uppermost position fully closing the upper opening of the container 10 and when the gate is fully closed the bridge piece 150 bridges contacts 151, closing the shunt circuit around the open contacts of cam operated switch 114, thereby again completing the circuit energizing solenoid 131 and again setting the motor 105 in rotation, cam operated switches 117 and 119 being in closed position during this operation.

The continued rotation of motor 105 opens the cam operated switch 115 and unless the magnetically operated tumbler switch 127 is closed, the holding circuit is broken stopping the motor. Switch 127 is normally closed and is held in open position during such time as another of the ejectors is operated. While another ejector operates, switch 127 is held in open position thereby preventing the shunt of the otherwise open cam operated switch 115 and preventing further rotation of the motor until the other ejector has ceased its operation. Assuming that switch 127 is closed, the motor continues to rotate closing cam operated switch 116 and opening the air valve 133 to admit air to the air cylinder 20 for the purpose of opening the discharge gate 17.

As air valve 133 is opened, switch 117 is also opened, breaking the circuit through holding solenoid 131 and interrupting further rotation of the motor 105 until the discharge gate has been fully opened, thereby

bridging the contacts 160 which are shunted across the contacts of switch 117. As contacts 160 are bridged the circuit is completed through cam switch 119 again energizing solenoid 131, closing the motor switch 108 and starting the motor. Cam operated switch 118 now closes, completing the circuit through the valve operating solenoid 140 and admitting air to the interior of the container to eject the contents through the open discharge gate 17. A slight further rotation of motor 105 opens switch 119 breaking the holding circuit and stopping motor 105.

As pressure is built up within the container 10, the switch arm of regulator switch 138, controlled by the pressure within the container 10, is moved to contact with contact 140 thereby energizing relay 147 and shifting all of the switches of this relay to their alternate position thereby establishing a circuit from main 102 through relay 147, cam operated switch 112 and out to main 101. Relay 146 is also energized throwing the switch arms to their alternate position and establishing a circuit up to switch 113 which is open.

As the pressure within the container drops, when the contents thereof have been completely ejected, the switch arm or regulator 138 is moved to contact 141 thereby completing the circuit from main 101, throwing contact arm 141 to close the circuit to the magnet of relay 147, which is thereby energized, restoring the contacts thereof to their normal position and completing the circuit from main 102 to relay 147, relay 146, through to relay 139, energizing the solenoid thereof which moves the contacts of relay 139 to open the circuit controlling the air pressure valve 140. The energizing of relay 139 closes its contact arm 142, thereby establishing a circuit from main 102 through holding solenoid 131 to switch 119 through switch 121 through contact arm 142 to switch 120, switch 115, switch 111, tumbler switch 126 and out to main 101, thereby again starting motor 105.

Motor 105 now closes air valve 133 and opens air valve 134 admitting air to the other side of cylinder 156 to move the discharge gate 17 to closed position. Switch 120 is closed by motor 105 and switch 121 is opened breaking the holding circuit and stopping motor 105 until the discharge gate 17 is fully closed and contacts 157 are bridged completing a shunt circuit across switch 121 again starting motor 105. Further rotation of motor 105 now closes the air valve 132 which permits the gate 35 to open, and during this time air valve 134 is being closed. Cam operated switch 122 is now opened by motor 105 and switch 123 is closed, resetting the magnetically operated switch 126 and returning it to its normal position. The next operation of motor 105 is to return all of the cam operated switches to their normal position as 130

shown in the figure of the drawing, and finally cam operated switch 111 is opened stopping the motor 105 until the container 10 is again filled with sewage.

5 A separate main control panel, shown in Fig. 6, is preferably provided which accommodates the interlocking mechanism for determining the sequence of the operation of the several ejectors and ejector panels, and as shown in this figure, the power is supplied by 10 a generator 100 which is connected with the mains 101, 102 and 103 leading to each of the individual control panels. The main control panel preferably comprises a motor 165 connected with a cam shaft 166 controlling switches 167 and 168, the energy supplied to the motor 165 being controlled by a manually actuated switch 169. As switch 169 is closed switches 167 and 168 are alternately opened 15 and closed, and a closing of switch 168 permits the continued operation of the left individual control panel, provided the circuit between contactors 170 and 171 is closed by switch 127. The operation of right individual 20 control panel is similarly controlled by switch 167 and contactors 172 and 173 which are connected with a switch similar to switch 127. In this way only one ejector can be operated at any one time and it is impossible 25 for sewage to be blown from one ejector into the other.

The invention in its broader aspects is not limited to the specific mechanism shown and described but departures may be made therefrom within the scope of the accompanying claims without departing from the principles of the invention and without sacrificing its chief advantages.

What I claim is:—

40 1. A sewage disposal system including in combination a plurality of ejectors, each comprising a container having an inlet and outlet, means for opening and closing said inlet and outlet, means for supplying air under pressure to said containers to eject sewage therefrom into a common outlet, interlocking means for preventing simultaneous operation of more than one ejector, and means for preventing air being supplied to the ejectors 45 while the inlet is open or the outlet is closed.

50 2. A sewage disposal system including in combination a plurality of ejectors, each comprising a container having an inlet and outlet, means for opening and closing said inlet and outlet, means for supplying air under pressure to said containers to eject sewage therefrom into a common outlet, interlocking means for preventing simultaneous operation of more than one ejector, means for preventing air being supplied to the ejectors while the inlet is open or the outlet is closed, and means for automatically setting said means in operation by filling the container with sewage.

55 3. A sewage disposal system including in

combination an ejector having an inlet and outlet and closure means for said inlet and outlet, means for supplying air under pressure to said ejector, and control means therefor comprising a motor shaft set in operation by filling the ejector with sewage and controlling the operation of the closures and air supply to first close the inlet, open the outlet, supply air to the container and thereafter close the outlet and open the inlet. 70

4. A sewage disposal system including in combination an ejector having an inlet and outlet and closure means for said inlet and outlet, means for supplying air under pressure to said ejector, and control means therefor preventing the supplying of air until the inlet is fully closed and the outlet is fully opened. 80

5. A sewage disposal system including in combination an ejector having an inlet and outlet and closure means for said inlet and outlet, means for supplying air under pressure to said ejector to force the material within the ejector out through the outlet, and control means therefor including means for opening the inlet and closing the outlet as soon as the pressure within the ejector decreases after ejecting material therefrom. 85

6. A sewage disposal system including in combination an ejector having an inlet and outlet and closure means for said inlet and outlet, means for supplying air under pressure to said ejector to force the material within the ejector out through the outlet, and control means therefor including means for closing the inlet, opening the outlet, turning on the air under pressure and thereafter closing the outlet and inlet. 95

7. A sewage disposal system including in combination an ejector having an inlet and outlet and closure means for said inlet and outlet, means for supplying air under pressure to said ejector to force the material within the ejector out through the outlet, and control means therefor including pneumatic means for concurrently closing the inlet and opening the outlet on filling the ejector with sewage and for restoring the parts to their original position as soon as the ejector is emptied. 105

8. A sewage disposal system including in combination an ejector having an inlet and outlet and closure means for said inlet and outlet, means for supplying air under pressure to said ejector to force the material within the ejector out through the outlet, and control means therefor including means for closing the inlet and opening the outlet on filling the ejector with sewage, means for turning on the air under pressure as soon as the inlet is fully closed and the outlet is fully opened, and means for restoring the parts to their original position on completion of the discharge of material from the ejector. 110

9. A sewage disposal system including in 120

combination an ejector having an inlet and outlet and closure means for said inlet and outlet, means for supplying air under pressure to said ejector to force the material within the ejector out through the outlet, and control means therefor including means for closing the inlet, means for closing the outlet, means for turning on the air under pressure to eject the sewage, means for closing the outlet, means for opening the inlet, and means for preventing operation of the means until the preceding means has fully accomplished its operation.

In testimony whereof, I have signed my
15 name to this specification.

FRANK J. KOCH.
